BRASSIERE PAD

Irwin Greenblatt, Blauvelt, N.Y., and Nicholas A. Marino, Chicago, Ill., assignors to Sears, Roebuck and Co., Chicago, Ill.

Filed Oct. 31, 1972, Ser. No. 302,593

Term of patent 14 years

Int. Cl. D2—01

U.S. Cl. D2—24

Fig. 1.

Fig. 2.

Fig. 3.

Fig. 4.

FIG. 1 is a front view of a brassiere pad showing our new design;

FIG. 2 is a rear view thereof;

FIG. 3 is a side elevation view from the right hand side of the pad;

FIG. 4 is a perspective view from the side with the perspective partially foreshortened;

FIG. 5 is a cross-sectional view taken on line 5—5 with respect to FIG. 2;

FIG. 6 is a rear perspective view of our design; and

FIG. 7 is a perspective view looking from line 7—7 of FIG. 1.

We claim:

The ornamental design for a brassiere pad, as shown and described.
